UNITED STATES PATENT OFFICE.

WESLEY W. BARNES, OF NEW YORK, N. Y., ASSIGNOR TO McLOUGHLIN BROTHERS, OF SAME PLACE.

COMBINATION TOY HOUSE OR STRUCTURE.

SPECIFICATION forming part of Letters Patent No. 258,212, dated May 23, 1882.

Application filed April 6, 1882. (No model.)

To all whom it may concern:

Be it known that I, WESLEY W. BARNES, a citizen of the United States, residing in the city, county, and State of New York, have invented certain new and useful Improvements in Toy Houses, of which the following is a specification.

My invention employs three boxes—one large containing-box and two smaller ones—with their covers and numerous panels and other accessories.

In the accompanying drawings, Figure 1 is a plan of the three boxes, the two smaller ones packed into the larger one. Fig. 2 is a side elevation thereof, partly in longitudinal section, cut on the line 2 2 in Fig. 1. Fig. 3 is a front elevation of one of the several panels employed. Fig. 4 is a like view of another species of panel. Fig. 5 includes a front and end view of one of two pilasters, and Fig. 6 includes a side and end view of one of two brackets. The remaining figures will be described hereinafter.

Let A designate the large box, and B B the two smaller ones. The box A is or may be provided with a fixed back or bottom, and is grooved at a, Fig. 2, for the reception of a sliding lid, which slides in from one end in the ordinary manner. One of its sides is pierced with four holes, c c, two at each end, those at one end being shown in Fig. 2.

Within the box A are fixed two upright cleats, d d, one being fastened to each end in the position shown in Fig. 1, and one side of each cleat being beveled, as shown. The purpose of these holes and cleats will be herein-after explained.

Each box B consists only of four pieces—two sides and two ends—there being no bottoms. Both the front and back are grooved at b b to receive sliding lids, these grooves being by preference reversed, as shown in Fig. 2, so that the top and bottom lids shall slide in opposite directions. The external length of each box B equals the external width of the box A, and the internal length of the latter is double the external length of the boxes B. Hence the two boxes B B fit into the box A end to end, as shown in Fig. 1, and the cleats d d confine

them in place laterally. These proportions of the boxes are of great convenience in packing them, at which time only they are fitted together, as in Figs. 1 and 2. The lids for the boxes B B are of such length, owing to the proportioning of the respective boxes, that their ends may engage the grooves a a in the box A, and hence one or more of them may be slid sidewise into these grooves; or they may be slid endwise into the grooves b b in either side of either box B. This capability admits of numerous different combinations being effected with comparatively few pieces. One of these lids or panels is shown in Fig. 3, and lettered C. On its front and back faces is painted or otherwise marked a window, door, or other architectural feature. The notch e will be hereinafter explained. Two of the panels should have these notches, and several others should be unprovided with them.

In Fig. 4 is shown a square panel, C', of which there should be two or more.

In Fig. 5 is shown a pilaster, E, whose length equals the internal width of the box A, and whose width should be approximately equal to one-half the difference between the sum of the widths of three panels, C C, and the external length of the box A. It is grooved at its sides, as shown in the end view, to receive the edges of the panels C C.

Fig. 6 shows a bracket, F, of which there are two, relatively reversed—that is, rights and lefts. Each is of a width equal to the space between the beveled side of the cleat d and the side of the box A nearest said cleat, so as to be able to slide into the intervening space, and its opposite edges are beveled to fit the cleats. Along one edge is a groove, f, and across each end is another groove, g. A slot h extends in from one end parallel with and close to one beveled edge, its width being sufficient to admit the thickness of the side piece of the box A. One corner of each bracket is cut off obliquely, as shown at i.

Having now described several of the elements of my invention, I will proceed to describe it in its entirety in one of the many forms of which it is capable. (Shown in Figs. 7 to 10 of the drawings.) This form has been

selected as embodying, perhaps more than any other, the most distinctive capabilities of my invention.

Fig. 7 is a plan of a simulated house or building built up from the parts already described, in connection with other accessory parts. Fig. 8 is a front elevation thereof. Fig. 9 is a side elevation, and Fig. 10 is a horizontal section cut along the line 10 10 in Figs. 6 10 and 9.

To build the edifice here shown I take first the box A, empty and without its lid, and into the grooves *a a*, I slide three panels, C, the middle one having no notch and the two end ones having each a notch at the outer side. The gaps between the panels are filled by inserting the pilasters E and sliding the panels together, so that their edges enter the grooves in the pilasters, as best shown in Fig. 10. I then set this box on its side, so that the architectural design on the panels shall be right side up, and I slide the two brackets F F in through the notches *e e*, the slot *h* of each bracket embracing the uppermost side of the box A. The brackets are placed, as shown, with their grooved sides facing each other. Into the horizontal grooves *f f*, I slide a thin strip or board, G, (shown in Figs. 7 and 8,) which is pierced with a row of holes, *j j*. Another piece 30 or board, G', like G, except that it is preferably thicker, is laid on the floor in front of the box A, and several round wooden pins, H H, are dropped through the holes *j j* of the board G, and their lower ends are entered into the holes in the board G'. A thin board, I, is then slid into the vertical grooves *g g*, and its lower edge rests on the board G. This simulates the pediment and the pins H H the columns of a building. I then take the two boxes 40 B B and slide certain panels, C or C', into their front grooves, *b b*, using one panel or another, according to what design is wished. I have shown panels C' below and panels C'' above, the latter being long panels with ornamental 45 tops, designed only as a finish for the fronts of the boxes B B, and not to be applied to the box A. Those shown in Fig. 8 have crenelated tops, while in Fig. 12 one is shown having its top cut in imitation of a steeple.

It will be observed by reference to Fig. 7 that each box B has a groove, *k*, extending along one side close to the back edge. In inserting the panels C' and C'', as just described, care is taken to insert them in the front grooves, *b b*, remote from these grooves *k k*. The boxes B B are then placed on the box A, to simulate the upper stories of the building, being stood on end with the two grooves *k k* facing each other. Another panel or panels are then slid down in the grooves *k k*, as shown. This gives the appearance of a deep recess in the front of the building. If only a shallow recess is desired, the boxes B B will be turned with their back sides toward the 65 front of the house, as shown in Fig. 11, which is a vertical cross-section through the center

of the structure, showing a modified arrangement of parts. The panels are here shown as omitted from the front of the box A, and the brackets F are inserted in the box A against the 70 cleats *d d*, with the inclined side *i* toward the front and turned uppermost. A thin board, J, is inserted in the vertical grooves *g g* of the brackets, and another board, K, which should be painted to simulate the shingles or tiles of 75 a roof, is placed in inclined position, its ends resting on the brackets and its lower edge against the strip J.

Fig. 12 is a front elevation of a church built from the elements of my invention. Fig. 13 is 80 an end elevation thereof. Fig. 14 is a fragmentary vertical cross-section cut along the line 14 14, and Fig. 15 is a bottom edge view of the roof-support shown in Fig. 14. This church is made by fitting the box A with its 85 own proper lid, which should be painted or marked to simulate the side of a church with its windows, setting the box on its side, as before, with the side having the holes *c c*, Fig. 2, uppermost. To this upper side are fitted two 90 inclined roof-supports, L L, each of which consists of a small piece of board, inclined on its upper edge and having two pins, *l l*, projecting from its lower edge and fitting into the holes *c c*. On these two supports the roof-board K is laid so that its painted side is presented in inclined position to the observer. 95

At the end of the church a steeple is constructed by setting one box, B, on the other, both being set on end, and both having panel-pieces slid into their fronts. The panels C' are made square to admit of their being turned either side up, according as the box B is to be stood on its end or side.

When it is desired to pack the parts of my 105 toy together the boxes B B are put into the box A, as shown in Fig. 1, the larger pieces G G', H H, I, J, and K, and perhaps C'', are put into the long space M, the smaller pieces are put into the boxes B B, and the lid of the box 110 is put on.

Having thus described my invention, what I claim as new, and desire to secure to my assignees by Letters Patent, is as follows:

1. The combination of box A, having grooves 115 *a a*, with a smaller box, B, of a length approximately equal to the width of the larger box, having grooves *b b*, and with panels C, capable of sliding lengthwise into the grooves *b b* and of sliding sidewise into the grooves *a a*, 120 substantially as set forth.

2. The combination of two boxes, B B; with a larger box, A, having an internal length approximately equal to the sum of the external lengths of the boxes B B, and an external 125 width approximately equal to the external length of each box B, and with panels C C, of a length approximately equal to the width of the box A, and a width approximately equal to the width of the boxes B B, substantially 130 as set forth.

3. The combination of two boxes, B B, hav-

- ing grooves *b b*, and each having a side groove, *k*, with panels *C C* and box *A*, substantially as set forth.
4. The combination of box *A*, cleats *d d*, fixed therein, brackets *F F*, having grooves *g g*, strip *J*, and roof-board *K*, substantially as set forth.
5. The combination of box *A*, brackets *F F*, having slots *h h*, and grooves *f f*, boards *G* and *G'*, and pins *H*, substantially as set forth.
6. The combination of box *A*, having holes *c c*, roof-supports *L L*, having pins *l l*, and roof-board *K*, substantially as set forth.
7. The combination of box *A*, having grooves *a a*, panels *C C*, adapted to slide sidewise into said grooves, and pilasters *E E*, having grooves in their side edges, substantially as set forth. In witnessss whereof I have hereunto signed my name in the presence of two subscribing witnuses.

WESLEY W. BARNES.
